E. G. GARTIN

FLUID PRESSURE MOTOR

Filed Feb. 20, 1920

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

FLUID-PRESSURE MOTOR.

Application filed February 20, 1920. Serial No. 360,137.

My invention relates to fluid pressure motors.

Its object is to provide an improved fluid pressure motor. A further object of my invention is to provide an improved percussive motor in which maximum drilling speed may be obtained. Another object of my invention is to provide an improved fluid pressure motor of the semi-valveless type in which fluid distribution will be effected in such manner as to provide a relatively uncushioned blow while yet providing ample fluid for a quick and positive return stroke. Further objects of my invention will appear during the description thereof.

In the accompanying drawings I have shown for purposes of illustration, one form which my invention may assume in practice.

In these drawings, Fig. 1 is a view taken on a central longitudinal plane through the cylinder of my motor and cutting the control valve thereof, the tool in which the illustrative form of my motor is embodied being of the type known as a stoper.

Fig. 2 is a similar view with parts in different positions.

In the illustrative embodiment I have shown a motor generally indicated by 1 having a cylinder member 2 provided with front and rear head members 3 and 4, respectively, there being mounted on the front head member a chuck housing 5 and on the rear head there is located a throttle valve 6 of well-known construction. This throttle valve serves to control a supply of fluid through the port 7 to the motor and through port 8 to the feed cylinder employed in stoping, the feed cylinder not being shown in these drawings as it is of well-known construction, but feeding the motor through a piston rod 9.

The cylinder member 2 of my motor is provided with differential bores, forming a large piston chamber 11 and a small piston chamber 12 and in these chambers reciprocates a piston having a large head 13 and a small rearwardly extended reduced portion 14, respectively fitting the bores 11 and 12. Formed in the rearward extension 14 and in the part adjacent the enlarged portion 13 is a reduced portion 15 serving to provide an annular passage 16 between its outer periph-

ery and the walls of the bore 12 through which fluid distribution is accomplished. An elongated inlet port 18 communicates 55 by means of a longitudinal fluid supply passage 17 with the port 7 formed in the throttle valve 6 and serves to admit fluid pressure at intervals, as hereinafter described, to the bores of the cylinder. Communicating with the smaller bore of the cylinder at a point toward the forward end thereof is a port 19 from which a rearwardly extended passage 20 leads to a port 21 located in the extreme rear end of the cylinder bore 60 65 12, this passage serving for the supply of fluid to the rear head 35 of the reduced portion 14 of the piston. Communicable with the rear end of the cylinder bore 12 by means of a port 22 which is controlled by a valve 23, is a passage 24 extending to the forward end of the larger bore of the cylinder and opening thereto by means of a port 25. The valve 23 is provided with a piston 26 reciprocating in a chamber 27 and the chamber 27 communicates by means of a passage 28 with the rear end of the large cylinder bore 11. An exhaust port 30 is provided in the wall of the large bore 11 of the cylinder in such position as to be opened by the 70 head 13 of the piston just before the instant of impact on the forward stroke and on the rearward stroke at a somewhat earlier instant in the stroke. Cooperating with the piston and projecting into the front end of the cylinder is a striking block 31 adapted to be struck by the piston at the end of its forward movement. At 33 I have indicated a cleansing fluid supply tube adapted to conduct cleansing fluid to a drill steel 34. It 75 80 85 will be understood that the relative position of the parts may be varied in reason in accordance with the requirements of design, and that the precise positions shown are not essential to the operation of the motor, the proportioning of the parts being subject to modification in the usual manner in the embodiment in various working forms of this construction.

The operation of this device is as follows: 100 Starting with the position of the piston as shown in Fig. 1, fluid pressure supplied under control of the throttle valve 6 enters the fluid pressure supply passage 17 and

passing into port 18, enters the cylinder by means of the annular passage 16 through which it passes forward to the large bore 11 of the cylinder. It acts herein on the 5 rear surface of the large head 13 of the piston, this surface being called hereafter 32. It simultaneously passes by way of port 19, passage 20, and port 21 to the rear end of the small bore of the cylinder where it acts 10 on the surface 35 of portion 14 of the piston. Fluid pressure also passes through passage 28 to the upper end of chamber 27 where it acts on the top head of piston 26 and maintains the valve 23 closed, thereby 15 closing port 22. From the construction illustrated, it will be seen that at the rear end of the piston stroke the portion 14 of the piston overruns by a slight amount the port 22. From the position shown in Fig. 20 1, the piston moves forward under the action of live pressure until the port 19 is closed by the forward end of the unreduced portion of part 14 of the piston, and expansion begins in the rear end of bore 12 of the cylinder. Port 18 is next closed and the piston 25 continues its movement entirely under expansive action of the fluid on surfaces 32 and 35. When the front end of the portion 14 of the piston closes port 19, communication 30 between the surfaces 32 and 35 of the piston is shut off and during further movement of the piston, the fluid works in the two chambers separately. Somewhat later in the stroke, the rear end of the portion 14 of the piston uncovers the rear end of the elongated port 18 and live fluid pressure 35 enters the chamber 12 of the cylinder bore and builds up a pressure therein. When the pressure becomes high enough, when acting 40 on the surface of valve 23 exposed through port 22 to overcome the reduced pressure in chamber 27, which pressure has been reduced due to expansion, live pressure will be permitted to pass by way of passageway 24 and port 25 to the front end of the cylinder. The precise moment of opening of valve 45 23 may be determined by proper proportioning of port areas and of the piston 26 in such manner that this valve will open prior 50 to opening of exhaust port 30, or its opening may be delayed until even after that event. Owing to the fact that pressure to effect the return stroke of the piston must pass through the chamber behind the portion 55 14 of the piston, in which expansion has greatly reduced the pressure, and must build up a pressure therein sufficient to open the valve 26, which pressure may, if desired, be less than the inlet pressure, it will be 60 obvious that fluid pressure will not be admitted to the front end of the bore 11 of the cylinder until the stroke of the piston has been almost completed and that such pressure as is admitted thereto will be 65 initially less than would be the case were admission to occur directly to passage 24 and not through the reduced pressure chamber in the rear end of the bore 12. As a result of this construction the piston will strike an almost uncushioned blow on the 70 plug 31. It will be noted that on the return stroke of the piston which will occur when the pressure in the forward end of the bore 11 of the cylinder acting on the full face 36 of the piston overcomes the pressures acting on the surfaces 35 and 32, the piston will move backwards, closing the exhaust port 30 and building up a cushion pressure until the port 18 is opened. After 75 the closure of the port 18 by the rear end of the part 14 of the piston, the pressure fluid in the rear end of the reduced bore 12 of the cylinder will be forced around into the front end of the cylinder in a well known manner and will aid in the operation of the motor. 80 At the moment when the front end of port 18 is opened, live pressure will pass into the rear end of the bore 11 of the cylinder and will build up therein a pressure in combination with the cushion pressure sufficient to 85 close the valve 23 against the pressure tending to hold it open, which pressure will have fallen off both through expansion in the front end of the cylinder and due to the opening of the exhaust port 30. Whether 90 the throwing of this valve shall be accomplished by the differences in pressures in the opposite ends of the chamber 11 of the cylinder prior to exhaust at the front end of the cylinder, or after exhaust has occurred from 95 the front end of this bore, is immaterial so far as operation of the motor is concerned and this feature may be regulated at the time of construction as the particular work requires. It is also obvious that closure of 100 port 22 may be effected before or after the opening of the front end of port 18, this being determined by the area of piston 26 and other factors. From the foregoing statements it will be seen that a motor is 105 provided in which a substantially uncushioned blow may be struck the steel, in which by expansion longitudinally through a reduced space in the cylinder the time of opening of a control valve for one end of the 110 cylinder may be varied, and in which by expansion of motive fluid for a return stroke through a reduced pressure space, the degree of cushion on the forward stroke may 115 be regulated and reduced. As the matter 120 of control of the front end of the large cylinder bore is largely independent of the position of the front end of port 18, the moment of cut off on the forward stroke may be made later, if desired, than would otherwise 125 be possible.

While I have in this application specifically described one form which my invention may assume in practice, it will be understood that this form of the same is shown for 130

purposes of illustration and that the invention may be modified and embodied in other forms without departing from its spirit or the scope of the appended claims.

5. What I claim as new and desire to secure by Letters Patent is:

1. A fluid pressure percussive motor comprising a cylinder, a piston reciprocable therein having a reduced shank, and fluid distribution means including ports and passages for supplying motive fluid to the ends of said cylinder to act on both sides of the piston for effecting reciprocation of said piston one of said passages having only a single 10 mouth or supply port alternately opened and closed by said shank and operative to conduct motive fluid to one side of said piston to effect a rearward stroke of the latter, and means normally tending to open by 15 pressure and held closed by the motive fluid at the other side of said piston to maintain said passage closed during a substantial portion of the forward piston stroke.

2. A fluid pressure motor comprising a cylinder having front and rear ends, a piston reciprocable in said cylinder, and fluid distribution means for effecting reciprocation of said piston including an inlet port alternately opened and closed by said piston, 20 passages communicable with said port for conducting motive fluid to both ends of said cylinder, and a valve controlling one of said passages, said valve controlled passage being adapted to conduct motive fluid 25 from one end of said cylinder to the other end thereof to effect a rearward stroke of said piston and having communication with each end of said cylinder at opposite sides of said inlet port through a single port only.

3. A fluid pressure motor comprising a cylinder having bores of two diameters, a piston having a head disposed in the larger bore and a reduced shank disposed in the smaller bore, and fluid distribution means 40 for supplying motive fluid to the ends of said cylinder for effecting reciprocation of said piston including passages alternately opened and closed by said shank for directly admitting motive fluid to the end of said shank and to the portion of the head adjacent said shank, a passage communicating with the smaller bore through only a single port for conducting motive fluid to the other side of said head, and a valve located 45 between the ends of said latter passage for controlling the flow of fluid therethrough, said latter passage being successively controlled by said shank and by said valve.

4. A fluid pressure motor comprising a cylinder having bores of two diameters, a piston having a head disposed in the larger bore and a reduced shank disposed in the smaller bore, and fluid distribution means 50 for supplying motive fluid to the ends of said cylinder for effecting reciprocation of

said piston including means for admitting live motive fluid to the rear surfaces of said piston to act thereon, a passage having communication with the smaller bore through a single port only and adapted to conduct 55 motive fluid to the forward end of said cylinder, and a valve for controlling the flow of fluid through said port, said valve being opened by pressure admitted past the rear end of said shank and being controlled 60 by the pressure acting on the rear surface of said piston head.

5. A fluid pressure motor comprising a cylinder having bores of two diameters, a piston having portions disposed in said bores, and fluid distribution means for effecting reciprocation of said piston including means to admit live motive fluid intermittently to both of said bores at the other side of said piston to effect a stroke of said 65 piston in one direction and to one of said bores at the other side of said piston to effect a stroke of said piston in the reverse direction, said last mentioned means comprising a passage having only a single 70 mouth or supply port, and controlling means therefor controlled by said piston and the differences in pressure of the live fluid acting in said bores to effect said first mentioned stroke.

6. A fluid pressure motor comprising a cylinder having bores of two diameters, a piston having a head disposed in the larger bore and a reduced shank disposed in the smaller bore, and fluid distribution means 75 for supplying motive fluid to the ends of said cylinder for effecting reciprocation of said piston including means intermediate the ends of the smaller bore for admitting live motive fluid to the rear surfaces of said piston to act thereon, a passage having communication with the smaller bore through a single port only and adapted to conduct fluid to the forward end of said cylinder, and a valve for controlling the flow of fluid 80 through said passage, said valve being moved to opened position by live motive fluid admitted past the rear end of said shank.

7. A fluid pressure motor comprising a cylinder having bores of two diameters, a piston having portions disposed in said bores, and fluid distribution means for effecting reciprocation of said piston including means to admit motive fluid intermittently to both of said bores at one side of said piston to effect a stroke of said piston in one direction and to the bore at the other side of said piston to effect the stroke of said piston in the reverse direction, said last mentioned means comprising a passage having only a single mouth or supply port, and controlling means therefor controlled by the differences in pressure of the live motive fluid acting in said bores to effect said first mentioned stroke.

8. A fluid pressure motor comprising a cylinder having bores of two diameters, a piston having a head disposed in the larger bore and a shank disposed in the smaller bore, and fluid distribution means for effecting reciprocation of said piston including means alternately opened and closed by said piston for admitting motive fluid to the pressure area on said shank and to the pressure area on said head adjacent said shank to effect a piston stroke in one direction, and means controlled by the live motive fluid acting on the pressure area on said shank and by the pressure acting on said pressure area on said head to admit a charge of motive fluid from the smaller bore to the opposite side of said piston head to effect a return stroke.

9. A fluid pressure motor comprising a cylinder, a piston therein having a pair of pressure areas for operating it in one direction and a single pressure area larger than either of said areas for operating it in the opposite direction, and fluid distribution means for effecting reciprocation of said piston including means to admit live motive fluid to both of said first mentioned pressure areas for different periods but to neither for a full stroke, and means to admit motive fluid to the last mentioned larger pressure area controlled by live motive fluid acting on one of said first mentioned pressure areas.

10. A fluid pressure motor comprising a cylinder, a piston therein, and fluid distribution means for effecting reciprocation of said piston including an inlet port, means formed in part on said piston for conducting motive fluid from said inlet port to act on said piston to effect opposite movements thereof, whereby at a given point in the piston stroke the admission of fluid acting to effect one stroke of said piston is controlled completely by said piston, and means including a valve for controlling the admission of fluid to effect the opposite stroke of said piston, said valve being controlled by said piston, all of the fluid effecting said opposite stroke flowing past said valve.

11. A fluid pressure motor comprising a cylinder, a piston therein, and fluid distribution means for effecting reciprocation of said piston including an inlet port, means formed in part on said piston for conducting motive fluid from said inlet port to act on said piston to effect opposite movements thereof, whereby at given points in the stroke of said piston the admission and cut off of fluid acting to effect one movement of said piston is controlled completely by the latter, and a valve for controlling the admission of fluid to effect opposite movement of said piston, said valve being controlled by said piston, all of the fluid effecting said opposite stroke flowing past said valve.

12. A fluid pressure motor comprising a cylinder, a piston therein, and fluid distribution means for effecting reciprocation of said piston including fluid inlet and conducting passages for effecting forward movement of said piston, said passages being completely closed by said piston during movement thereof thereby causing the pressure trapped in the rear end of said cylinder to expand down to a pressure materially less than inlet pressure, means for conducting motive fluid to the front end of said cylinder longitudinally through the rear end of said cylinder which contains the reduced pressure whereby the cushioning action of said fluid on the forward stroke of said piston may be minimized, and means for maintaining said last mentioned means closed during a substantial portion of the forward piston stroke.

13. A fluid pressure motor comprising a cylinder having bores of two diameters, a piston having a head disposed in the larger bore and a shank disposed in the smaller bore, and fluid distribution means for effecting reciprocation of said piston including means to admit motive fluid to the several pressure areas of said piston comprising a single inlet port communicating directly with the smaller bore and alternately opened and closed by said shank, a plurality of fluid distributing passages, at least one of said passages being controlled completely by said piston, and a valve for controlling at least one other of said passages.

14. A fluid pressure motor comprising a cylinder having bores of two diameters, a piston having a head disposed in the larger bore and a shank disposed in the smaller bore, and fluid distribution means for effecting reciprocation of said piston including means to admit motive fluid intermittently to the several pressure areas of said piston comprising a single inlet port communicating with the smaller cylinder bore, a plurality of passages one of which being controlled completely by said piston, and a valve for controlling another of said passages.

15. A fluid pressure motor, a cylinder having communicating bores of two diameters, a piston in said cylinder having a head disposed in the larger of said bores and a shank disposed in the smaller thereof, and fluid distribution means for effecting reciprocation of said piston including means for supplying live motive fluid to each of said bores at one side of said piston for only a part of the piston stroke to effect said stroke in one direction and to the bore at the other side of the piston to effect a return stroke of said piston, and a valve for controlling said supply means for effecting one of said strokes of said piston.

16. A fluid pressure motor comprising a cylinder having communicating bores of two diameters, a piston in said cylinder having a

- head disposed in the larger of said bores and a shank disposed in the smaller thereof, and fluid distribution means for effecting reciprocation of said piston including a single 5 inlet port alternately opened and closed by said shank, means for supplying motive fluid to the end of said shank and to the portion of the head adjacent said shank for effecting one stroke of said piston, a passage 10 for supplying fluid to the other side of said head to effect a return stroke of said piston, said passage communicating with the smaller bore adjacent the rear end thereof, and a valve for controlling said passage.
- 15 17. A fluid pressure motor comprising a cylinder having communicating bores of two diameters, a piston in said cylinder having a head disposed in the larger bore and a shank disposed in the smaller bore, and fluid 20 distribution means for effecting reciprocation of said piston including a single inlet port alternately opened and closed by said shank, means for supplying motive fluid to the end of said shank and to the portion of 25 said head adjacent said shank for effecting one stroke of said piston, a passage for supplying fluid to the other side of said head to effect a return stroke of said piston, said passage communicating with the smaller bore adjacent the rear end thereof, and a 30 valve controlling the communication of said latter passage with said bore.
18. A fluid pressure motor comprising a cylinder having a plurality of communicating 35 bores of different diameters, a piston having a head disposed in the larger bore and a shank disposed in the smaller bore, and fluid distribution means for effecting reciprocation of said piston including a source 40 of motive fluid supply, means for supplying motive fluid to both of said bores at one side of said piston to effect forward stroke of said piston, means for supplying motive fluid through said smaller bore to said large bore 45 at the other side of said piston to effect the return stroke of said piston, a valve controlling said last mentioned fluid supply means, and means for maintaining said valve in its opened position for a period after communication 50 between said source of motive fluid supply and said second mentioned means is interrupted.
19. A fluid pressure motor comprising a cylinder having front and rear ends, a piston 55 in said cylinder, and fluid distribution means for supplying motive fluid to the ends of said cylinder for effecting reciprocation of said piston including an inlet port through which motive fluid for both ends is supplied alternately opened and closed by 60 said piston, a passage having only a single mouth supply port overrun by said piston and adapted when in communication with said inlet port to conduct motive fluid to one end of said cylinder to effect one stroke of 65 said piston, and means controlled by the motive fluid in the other end of said cylinder to maintain said passage closed during a substantial portion of the other piston stroke.
20. A fluid pressure motor comprising a cylinder having a large forward bore and a reduced rearward bore, a piston in said cylinder having a head disposed in said large bore and a reduced shank disposed in said reduced bore, and fluid distribution means for 70 supplying motive fluid to said cylinder to effect reciprocation of said piston including a fluid inlet port communicating with said reduced bore and alternately opened and closed by said shank, a passage having only a single mouth communicating with said reduced bore and operative to conduct motive fluid to the forward end of said large bore to effect rearward stroke of said piston, a fluid 75 conducting groove formed on said shank for conducting motive fluid to the rear end of said large bore, a passage controlled by said shank for connecting said groove with the rear end of said reduced bore, a valve for controlling the flow of motive fluid through said first mentioned passage, and a passage constantly communicating at the rear end of said large bore and with said valve for maintaining the latter in its closed position during a substantial 80 portion of the forward piston stroke.
21. A fluid pressure motor comprising a cylinder having bores of two diameters, a piston therein having a head disposed in the larger bore and a shank disposed in the smaller bore, and fluid distribution means for effecting reciprocation of said piston comprising means for causing expansive action of the pressure fluid in the smaller bore during the forward piston stroke, means for 85 admitting pressure fluid through the smaller bore to the forward end of said cylinder, and means for maintaining said last mentioned means closed during a substantial portion of the forward piston stroke and for 90 opening said means prior to the completion of said stroke.
22. A fluid pressure motor comprising a cylinder having communicating bores of two diameters, a piston having a head disposed in the large bore and the reduced shank disposed in the small bore, and fluid distribution means for effecting reciprocation of said piston comprising a fluid inlet, a passage for connecting said small bore 100 with said large bore, a passage opening into one end of said small bore, said shank being adapted to connect said small bore and the rear end of said large bore by way of said last mentioned passage, said piston being 105 movable in opposite positions to place either of said passages in communication with said inlet while closing the other of said passages, and means for maintaining said first 110 mentioned passage closed during a substantial portion of the forward piston stroke.
23. A fluid pressure motor comprising a cylinder having communicating bores of two diameters, a piston having a head disposed in the large bore and the reduced shank disposed in the small bore, and fluid distribution means for effecting reciprocation of said piston comprising a fluid inlet, a passage for connecting said small bore 120 with said large bore, a passage opening into one end of said small bore, said shank being adapted to connect said small bore and the rear end of said large bore by way of said last mentioned passage, said piston being 125 movable in opposite positions to place either of said passages in communication with said inlet while closing the other of said passages, and means for maintaining said first 130 mentioned passage closed during a substantial portion of the forward piston stroke.

tial portion of the forward piston stroke.

23. A fluid pressure motor comprising a cylinder having communicating bores of different diameters, a piston having a head disposed in the large bore and a reduced shank disposed in the smaller bore, and fluid distribution means for effecting reciprocation of said piston comprising conduit means communicating with said small bore and adapted to admit fluid to the rear end of said large bore to act on the rear surface of said piston head, a fluid inlet communicating with said small bore and adapted to admit fluid to the rear end of said large bore when communication between said inlet and said small bore is closed, a conduit for conducting fluid from said inlet to the forward end of said large bore, and a valve controlled by the pressure at the rear side of said piston head for maintaining said latter passage closed during a substantial portion of the forward piston stroke.

24. A fluid pressure motor comprising a cylinder having front and rear ends, a piston reciprocable in said cylinder having an enlarged head and a reduced shank, and fluid distribution means for effecting reciprocation of said piston including a fluid inlet port, means including passages for conducting fluid to the opposite ends of said cylinder to act on the pressure areas on said head and said shank, said passages and said inlet port being alternately connected and interrupted by said shank, and means for maintaining the passage connecting the inlet with the forward end of said cylinder

closed during a substantial portion of the forward piston stroke.

25. A fluid pressure motor comprising a cylinder having front and rear ends, a piston reciprocable in said cylinder having an enlarged head and a reduced shank and fluid distribution means for effecting reciprocation of said piston including a fluid inlet port, means including passages for conducting fluid therefrom to the opposite ends of said cylinder to act on the pressure areas on said head and shank, said conducting means and said inlet port being alternately connected and interrupted by said reduced shank, and a valve for controlling flow of fluid through one of said fluid conducting passages.

26. A fluid pressure motor comprising a cylinder having communicating bores of different diameters, a piston therein having a head disposed in the large bore and a reduced shank disposed in the small bore, and fluid distribution means for effecting reciprocation of said piston including a fluid inlet port, passages for conducting fluid therefrom to the bores of said cylinder, said conducting means and said inlet port being alternately connected and interrupted by said shank, the pressure fluid expanding in passing through said smaller portion of the bore to one of said passages, and a valve in said latter passage for maintaining the same closed during a substantial portion of the forward piston stroke.

In testimony whereof I affix my signature.

ELMER G. GARTIN.

CERTIFICATE OF CORRECTION.

Patent No. 1,679,128.

Granted July 31, 1928, to

ELMER G. GARTIN.

It is hereby certified that error appears in the printed specification of the above numbered patent requiring correction as follows: Page 3, line 14, claim 1, after the syllable "ton" insert a comma; same page, line 84, strike out the words "the other" and insert instead the word "one"; and that the said Letters Patent should be read with these corrections therein that the same may conform to the record of the case in the Patent Office.

Signed and sealed this 25th day of September, A. D. 1928.

(Seal)

M. J. Moore,
Acting Commissioner of Patents.
